UNITED STATES PATENT OFFICE.

MARCUS EATON, OF CIRCLEVILLE, OHIO.

LIFTING-JACK.

SPECIFICATION forming part of Letters Patent No. 277,247, dated May 8, 1883.

Application filed October 23, 1882. (Model.)

To all whom it may concern:

Be it known that I, MARCUS EATON, of Circleville, in the county of Pickaway and State of Ohio, have invented a new and Improved 5 Lifting-Jack, of which the following is a full, clear, and exact description.

In this improved lifting-jack the lifting and holding pawls are formed on loose bands or thimbles surrounding the sliding post having 10 the toothed rack, and they engage the rack by being tilted sidewise and disengage it by falling back level. An eccentric lever is employed for working the lifting-pawl, and there 15 is a latch for causing the holding-pawl to engage the rack when required, and allowing it to disengage when it is desired to work the post down, with the load on it, by the lever. The sliding post is provided with a cross-beam attachment, to be employed when it is desired 20 to lift the axle of a light carriage, so as to raise both wheels at the same time, and a removable foot-brace to steady the jack is also provided, all as hereinafter fully described.

Reference is to be had to the accompanying 25 drawings, forming part of this specification, in which similar letters of reference indicate corresponding parts in all the figures.

Figure 1 is a perspective view of a lifting-jack constructed according to my invention. 30 Fig. 2 is a detail of the sliding post and pawls in section; and Fig. 3 is a view of the reverse side of the jack, showing a modified form of latch for controlling the lower pawl of the lifting-post.

The stand *a* may be constructed in any approved way, with suitable guides in which to enable the lifting-post *b* to slide up and down, as required in such machines. The said post is provided with the usual toothed rack, *c*, to 35 be engaged by the lifting-pawl *d* and the holding-pawl *e*, said pawls being formed on rings or bands *f*, surrounding the post loosely, so as to slide on the post readily. The lifting-pawl *d* is arranged above the eccentric lever 40 *g*, so that it rests at *h* on the lever, and thereby tilts against the rack-bar to engage it for raising the post by the lever, and when the lever-head swings down the pawl slides down the post along with it. The holding-pawl *e* 45 rests similarly, at *i*, on the face *j* of a latch, *k*, when it is to engage the rack *c* for holding it;

but when it is desired to allow said pawl to disengage the rack and allow the post to descend, the latch is shifted forward to the right hand, so that notch *l*, which is lower than the bars *m* of the frame, swings under the pawl, allowing it to fall flat on said bars *m*, in which position the pawl swings out of and does not engage the teeth *c*, thus enabling the post to descend. The lever *g* will also allow pawl *d* to 55 drop out of the teeth by swinging the handle *g'* up to the vertical line, or thereabout, when the face *h'* of said lever is lower than the frame-bar *h*, on which the top ring, *f*, rests, and the ring then falls, disengaging the pawl 60 *d* and allowing the post to drop, provided latch *k* is set for the disengagement of pawl *e*, the arm of said latch being swung downward, as hereinafter described.

To raise the post the latch is set in the position shown in Fig. 1 and allowed to remain. To let the post drop quickly when not loaded, the bands *f* are lifted by hand opposite to the pawls, which disengage them; but when it is desired to work the loaded post down gradually by the lever, the lever is made, in its downward stroke, to collide with the arm *n* of the latch *k* and swing it over, so that notch *l* allows pawl *e* to fall on bars *m* and disengage with the rack, so that by raising the lever the 70 post will descend. When the lever-handle is near the end of the upstroke the point *o* collides with the arm *n* and swings it back to the position in which it is represented, thrusting face *j* under pawl *e* and causing it to engage 75 with the rack, so that by raising the lever the post will descend. When the lever-handle is near the end of the upstroke the point *o* collides with the arm *n* and swings it back to the position in which it is represented, thrusting face *j* under pawl *e* and causing it to engage 80 with the rack, so that by raising the lever the post will descend. When the lever-handle is near the end of the upstroke the point *o* collides with the arm *n* and swings it back to the position in which it is represented, thrusting face *j* under pawl *e* and causing it to engage 85 with the rack, so that by raising the lever the post will descend. When the lever-handle is near the end of the upstroke the point *o* collides with the arm *n* and swings it back to the position in which it is represented, thrusting face *j* under pawl *e* and causing it to engage 90 with the rack, so that by raising the lever the post will descend. When the lever-handle is near the end of the upstroke the point *o* collides with the arm *n* and swings it back to the position in which it is represented, thrusting face *j* under pawl *e* and causing it to engage 95 with the rack, so that by raising the lever the post will descend. When the lever-handle is near the end of the upstroke the point *o* collides with the arm *n* and swings it back to the position in which it is represented, thrusting face *j* under pawl *e* and causing it to engage 100 with the rack, so that by raising the lever the post will descend.

When it is desired to use the jack to lift both wheels of one axle off the ground at once,

I apply a cross-beam, *q*, to the top of the post, with braces *s* extending from the ends down to the lower end of the post, where they are attached to it by a bolt, *t*, which enables the beam *q* to be put on and taken off at will.

In Fig. 3 I have represented at *k'* a modified form of lever or latch which I propose to employ instead of latch *k* in some cases, said latch to be placed on the opposite side of the jack, and to be used for disengaging pawl *e* by lifting up the ring *f* on that side, and for engaging said pawl by dropping the ring, the bar *m* of that side being slightly lower than the one on the other side, or the lower edge of the ring being a little higher to allow the same to fall into the notches. This latch *k'* is pivoted to the frame of the jack at *m'* and rests on the stud-pin *n'*. When this latch is used latch *k* may be swung down so that the part *l'* will rest under pawl *e*, and said latch will be inoperative.

Near the lower end of the post *b*, I have attached a bracket, *o'*, to prevent the post from being accidentally lifted out of the jack, the said bracket coming in contact with the lower edge of a bar, *m*, if the post is lifted too high. The bracket also serves a useful purpose by enabling the operator to raise or lower the post by the toe of his foot when his hands are engaged, and it may be necessary to do so.

g² represents a cross-stay attached to one of the legs *a*, and forming a base to prevent the jack from falling sidewise. It is to be detachably connected by a bolt at *p'* and a notch or yoke at *q³* over a headed bolt, *q'*, fixed to the frame *a*, in order that it may be quickly dispensed with when not required. This cross-stay attachment is especially intended to be used, together with the top bar, *q*, for forming a base for the jack while hoisting two wheels at once. These attachments are intended particularly for carriage-makers' use, with whom it is customary to have all the wheels lifted off the floor while varnishing the gearing, using trestles and the like, which cannot be removed before the varnish is dry without injury to the varnish by the hands, while with this contrivance the carriage can be let down

on the floor at any time without touching the varnished parts.

Having thus described my invention, what I claim as new, and desire to secure by Letters Patent, is—

1. The combination of ring-pawls *d e* with the sliding rack-post *b*, lever *g*, and rest *j*, substantially as described.

2. The combination of ring-pawls *d e* with the sliding rack-post *b*, lever *g*, rest *j*, and bar-rests *m h²*, the rest *j* being adjustable to and from under the pawl *e*, substantially as described.

3. The combination of latch *k*, having rest *j* and notch *l*, with the holding-pawl *e* and rests *m*, substantially as described.

4. The latch *k*, having rest *j* and notch *l*, and arm *n*, in combination with holding-pawl *e* and the lifting-pawl lever *g*, said lever having point *o*, and being arranged to actuate said latch, substantially as described.

5. The combination of latch *k*, having rests *j* and *j'*, and notch *l* and rest *l'*, with the pawl *e*, substantially as described.

6. The combination of latch *k*, having points *w*, with the pawl *e* and bar *m*, said bar having indentations *x*, substantially as described.

7. The combination of lever-latch *k'* with the ring-pawl *e* and the lifting-post *b*, substantially as described.

8. The lever *g*, having high face and low face *h'*, in combination with ring-pawl *d*, lifting-post *b*, and bar-rests *h²*, substantially as described.

9. The combination of bracket *o'* with the post *b* and bar *m* of a lifting-jack, substantially as described.

10. The detachable base-stay *q²*, combined with the frame of the lifting-jack, substantially as and for the purposes set forth.

11. The combination of beam *q* and braces *s* with the sliding post *b* of a lifting-jack, the said beam being detachably connected to said post, substantially as described.

MARCUS EATON.
